UNITED STATES PATENT OFFICE.

HUBERT J. FARNHAM, OF WEST HAVEN, CONNECTICUT, ASSIGNOR TO THE PRICE & LEE COMPANY, OF NEW HAVEN, CONNECTICUT, A CORPORATION.

CARD-HOLDER.

1,394,157.

Specification of Letters Patent.

Patented Oct. 18, 1921.

Application filed January 11, 1921. Serial No. 436,429.

To all whom it may concern:

Be it known that I, HUBERT J. FARNHAM, a citizen of the United States, residing at West Haven, in the county of New Haven 5 and State of Connecticut, have invented a new and useful Improvement in Card-Holders; and I do hereby declare the following, when taken in connection with the accompanying drawings and the characters of 10 reference marked thereon, to be a full, clear, and exact description of the same, and which said drawings constitute part of this application, and represent, in—

Figure 1 a perspective view of a card holder constructed in accordance with my 15 invention and shown as detached.

Fig. 2 a plan view of a file provided with a series of holders constructed in accordance with my invention.

Fig. 3 a sectional view on line 3—3 of Fig. 2.

Fig. 4 a perspective view showing a modified form of card holder and a clip for use in connection with the same.

This invention relates to an improvement 25 in cardholders and particularly to holders adapted to permit the cards to be turned from one position to another. In making up directories cards containing the names 30 of residents and business offices are arranged in order of streets, and subsequently rearranged alphabetically for the printer. The object of this invention is to provide a holder which is adapted for use by can- 35 vassers, but also for use by the printer, and the invention consists in construction as hereinafter described and particularly recited in the claim.

The holders proper are formed from a 40 single piece of wire, the ends bent at right angles from points at equal distances from the center, so as to form a lip 5, both ends of the wires are then turned upward to form posts 6 and 7, bowed forward and thence 45 downward forming posts 8 and 9, connected by arches 10 and 11; the ends 12 and 13 of the wires are thence carried forward in the plane of the lip 5. In other words, arches are formed in the holder between the forward and rear ends.

These card holders are adapted for use in file cases, including a fixed strip 14, beneath

which the lips 5 may extend, the extreme ends of the wires 12 and 13 adapted to pass through clearance notches 15 and 16, formed 55 in a slide-bar 17, which is adapted to be moved by suitable key mechanism 18, so as to move the notches 15 and 16 out of line with the ends of the wires, so as to firmly lock them in position. 60

Generally, these files are adapted to contain several card holders. Before inserting the holders into the file, cards are placed thereon, these cards being perforated to pass over the ends of the wires and lie one upon 65 the other, with the posts extending upward through them. The cards are thus free to be moved from the forward posts to the rearward posts, or vice-versa. If it is desired to set up type from the cards themselves, 70 the card holders may be removed from the file and inserted into a clip 19, as shown in Fig. 4 of the drawings, this clip having a block 20, with notches to receive the ends of the wires, and at the opposite end with 75 a spring flange 21, with which the lip 5 may engage and, as also shown in Fig. 4 of the drawings, the lip 5 may be a long lip, or in other words, the arches may be formed midway between the ends of the wires and 80 the lip at the center thereof. With the cards held as in a clip, as shown in Fig. 4 of the drawings, they are in convenient position for use by a typesetter, who may turn the cards from a position at one side of the 85 arches to the opposite side.

While describing the device as used in obtaining data for directories and for use by printers, it is obvious that the holders as described may be used for a variety of 90 purposes where cards are employed.

I claim:

The combination with a card holder formed from a single piece of wire and comprising a lip, parallel arches and ends, of a 95 holder provided with means for engaging said lip and the ends of the said wire.

In testimony whereof, I have signed this specification in the presence of two subscribing witnesses.

HUBERT J. FARNHAM.

Witnesses:

C. E. WILLETT,
CHARLES L. HEATON.
